UNITED STATES PATENT OFFICE.

PATRICK E. NOLAN AND MORTEN MORTENSON, OF SUPERIOR, WISCONSIN,
ASSIGNORS OF THREE-FIFTHS TO DAVID E. ROBERTS, TAYLOR H. WOLF-
FORD, AND WILLIAM H. LOCKE, OF SUPERIOR, WISCONSIN.

DREDGING APPARATUS.

SPECIFICATION forming part of Letters Patent No. 697,215, dated April 8, 1902.

Application filed July 24, 1900. Serial No. 24,661. (No model.)

To all whom it may concern:

Be it known that we, PATRICK E. NOLAN and MORTEN MORTENSON, citizens of the United States of America, residing at Superior, in the county of Douglas and State of Wisconsin, have invented certain new and useful Improvements in Dredging Apparatus, of which the following is a specification.

This invention relates to dredging apparatus, and more particularly to that class in which the material is broken up by passing through a sieve and then being mixed with water and pumped to any desired point through pipes.

15 The object of this invention is to provide a dredging apparatus adapted to receive the dirt, &c., from any form of dredging-machine and after pulverizing the earthy material to mix it with water in order that it may be pumped through pipes to any desired point.

20 With these object in view and such others as may hereinafter appear our invention consists in the particular construction of the various parts and in the novel manner of combination and arrangement of said parts, all of which will be fully described, and specifically pointed out in the appended claims, which are intended to accord in their terms, spirit, and meaning with the prior state of the art 25 and the existing law.

20 In the drawings forming a part of this specification, Figure 1 is a side elevation. Fig. 2 is a vertical sectional view. Fig. 3 is a top plan view. Fig. 4 is a detail view of the rollers. Referring by letters to the drawings, A represents a tank or basin having mounted therein approximately near its bottom upon rollers B a steel hoop or band C, to which is secured a heavy iron hemispherical screen D. This 35 hoop or band is provided with cog-teeth E, adapted to mesh with the pinion F, mounted on the shaft G, which projects through the wall of the tank and is adapted to be driven by any suitable power. Projecting through the wall of the tank above the screen D is a jet-pipe H, which throws the water with force 40

against the dirt deposited on the screen. After the dirt has been sufficiently dissolved to pass through the screen it drops to the bottom of the tank, where it mingles with the 50 water furnished by the intake-pipe I and is drawn out by the suction-pipe J, which may be lengthened or shortened, so as to convey its load to any desirable point.

Changes in the form, proportion, and minor 55 details of construction may be resorted to without departing from the principle or sacrificing any of the advantages of the invention.

It will thus be seen that we provide a conveyor which may be used with any form of dredging-machine, one that is exceedingly cheap and simple in its construction and will efficiently perform all of its intended functions. 60

Having thus described the various features of our invention, what we claim as new and useful, and desire to secure by Letters Patent, is—

1. In a dredging apparatus, a tank having a 70 hemispherical screen mounted upon rollers therein, a jet-pipe mounted in the wall of the tank above the said screen, an intake-pipe mounted in the wall of the tank below the said screen, a suction-pipe, and mechanism 75 for revolving the screen, substantially as shown and described.

2. In a dredging apparatus, a tank having a jet-pipe and intake and suction pipes mounted in its wall, a revolving hemispherical screen 80 mounted upon rollers within the tank intermediate the jet-pipe and the intake and suction pipes, and mechanism for revolving the screen, substantially as set forth.

In testimony whereof we hereto set our 85 hands in the presence of two witnesses.

PATRICK E. NOLAN.
MORTEN MORTENSON.
